UNITED STATES PATENT OFFICE.

FRED SALINGER, OF DES MOINES, IOWA.

ADDING-MACHINE.

No. 888,749.

Specification of Letters Patent.

Patented May 26, 1908.

Application filed April 18, 1907. Serial No. 368,853.

To all whom it may concern:

Be it known that I, FRED SALINGER, a citizen of the United States, residing at Des Moines, in the county of Polk and State of Iowa, have invented a certain new and useful Adding-Machine, of which the following is a specification.

The object of my invention is to provide an adding machine that will print the numbers in properly arranged columns, and that may easily and quickly be operated to print the totals of the numbers at any desirable time, and that may be shifted to bring all of the adding wheels back to starting position, and that will visibly indicate to the operator the position of each adding wheel at all times.

My object is primarily to provide a machine of this kind of simple, durable and inexpensive construction.

My invention consists in certain details in the construction, arrangement and combination of the various parts of the device whereby simplicity and durability of construction are provided, and at the same time a machine is produced capable of accomplishing all of the desirable results of the more complicated and expensive machines as hereinafter more fully set forth, pointed out in my claims and illustrated in the accompanying drawings, in which—

Figure 1 shows a top or plan view of the complete machine embodying my invention, a part of the casing being broken away to show the interior construction. Fig. 2 shows a central, longitudinal sectional view of same. Fig. 3 shows a side elevation of same. Fig. 4 shows a detail side view illustrating the means for advancing the paper. Fig. 5 shows a detail side view through the shaft of the adding wheels, showing one of the adding wheels thereon, and illustrating the notch and lug device by which the adding wheel may be returned to normal position. Fig. 6 shows a similar view of the opposite side of the adding wheel, showing the ratchet device for operating the adjacent adding wheel for the purpose of carrying totals. Fig. 7 shows a detail plan view, illustrating the shaft of the adding wheels, and the spacing bars thereon for separating the adding wheels. Fig. 8 shows an enlarged detail view through a part of the machine frame adjacent to the shaft of the adding wheels, showing some of the adding wheels in section, and some in elevation, and illustrating

the arrangement by which totals are carried from one wheel to the other. At the bottom of this figure the printing hammers are shown in solid lines adjacent to the segments from which numbers are printed, and the dotted lines show the positions of these printing hammers adjacent to the adding wheels from which the totals are taken. Fig. 9 shows a side view illustrating the device for normally locking the shaft of the adding wheels, and for releasing and turning the said shaft for clearing the adding wheels and returning them to normal position. Fig. 10 shows a rear elevation of the entire machine with part of the paper roller broken away. Fig. 11 shows a detail sectional view illustrating the key bars for printing totals, and the arrangement by which a depression of one of the key bars will cause a movement of all of the printing hammers to the right of the key bar depressed, so that the entire total may be printed by a single operation. The dotted lines in this figure show the key bar in the fourth column depressed, and all of the other key bars to the right correspondingly depressed by it. Fig. 12 shows a face view of the three printing wheels to the left of the machine illustrating the position of the periods on the second wheel to indicate decimal points. Fig. 13 shows a detail perspective view of the mechanism for operating the printing hammers, and for shifting the carriage that supports the printing hammers and paper holding devices. Fig. 14 shows a detail view illustrating the mechanism for clearing the adding wheels and returning them to normal position, the pawl being shown in position for permitting the pin on the adding wheel to pass it. Fig. 15 shows a similar view with the pawl in position to engage and stop the pin on the adding wheel. Fig. 16 shows a detail plan view of the shaft for supporting the said pawls, and also showing a number of pawls in position on said shaft. Fig. 17 shows a detail plan view illustrating the lever for shifting the ribbon supporting device. Fig. 18 shows a detail view illustrating the part of the movable carriage for supporting the printing hammers and associated parts, and the means for shifting said carriage. Fig. 19 shows an enlarged detail view of one of the key bars.

Referring to the accompanying drawings, I have used the reference numeral 10 to indicate the main frame of the machine. Mounted in the frame is a shaft 11 for supporting

the levers of the printing segments. I have provided one of these levers for each column of key bars. The body portion of the lever is indicated by the numeral 12, and normally 5 inclines upwardly at its front end, its rear end being provided with a segmental printing arm 13, having on its front face a series of cog teeth 14, and having on its outer face a series of type 15, the upper type having the 10 numeral "0", the next the numeral "1", and so on. The rear end of the lever 12 is normally held downwardly by means of the spring 16. Obviously, if the forward end of the lever is moved down a short distance, the 15 second type from the top of the segmental bar 13 will be moved to printing position, and if moved down to its lower limit, the last type of the segmental bar 13 will be moved to printing position. I have provided for operating these levers the required distance by 20 means of a series of key bars for each of the levers 12. These key bars are each indicated by the numeral 17 and are slidably mounted in the top of the frame and in a supporting 25 bar 18. Each is normally held to its upper limit by means of a spring 19, and the shoulder 20 is formed on each as clearly shown in Fig. 19.

The first key bar indicated by the numeral 30 21 is designed to print the numeral 0, and is not provided with any notch, and does not affect the lever 12. The adjoining key bar has its notch 20 near its upper end, as clearly shown in Fig. 2, so that when it is depressed to its 35 full limit it will move the lever 12 only slightly, sufficient to elevate the segmental bar 13 to the distance required for bringing the second type into printing position. The shoulders 20 are arranged in different position 40 on all of the key bars 17 so that each when moved to its lower limit will operate the lever 12 in such manner as to bring the corresponding type to printing position.

I have provided for printing from the 45 type on the segmental bars 13 as follows: Mounted beneath the sliding key bars is a crank shaft 22, having crank arms in position to be engaged by the key bars 17 when depressed. On the rear end of each of the 50 crank shafts 22 is a crank arm 24. The numeral 25 indicates a carriage slidingly mounted in the frame, to move transversely thereof, and carried upon this carriage are the uprights 26. These uprights support a 55 roll of paper 27, and a loose roller 28, around which the sheet of paper is passed. The guide devices 29 and 30 are provided for holding the paper in position. A ribbon and ribbon supporting device is also provided as will 60 hereafter appear. Mounted upon the carriage 25 is a series of supports 31, to each of which I have pivoted a printing hammer 32. This hammer is normally held away from the type by means of the spring 33. Each hammer 65 is formed with a slot 34 into which the

crank shaft 24 is placed. By this construction, a depression of any one of the keys 17, or the key 21, will operate to first set the type bearing segments 13 to proper position, and will then operate the printing hammers. 70 The crank arms 24 are made long enough so that the carriage 25 may be shifted transversely of the machine to the required amount without affecting the operation of the printing hammer. 75

The ribbon support comprises two brackets 35, mounted at opposite sides of the machine frame, and containing the shaft 36, having a ribbon spool 37 at its top, and a bevel pinion 38 at its lower end. These 80 brackets 35 are fixed to the shafts 39 and 40, which are slidably mounted in the frame, and I have provided for sliding the shafts as follows: Pivoted to one side of the machine frame is a lever 41, connected by a rod 42 85 with a bell crank lever 43, fulcrumed to a bracket 44, on one of the uprights 26. The other end of the bell crank lever is connected to the brackets 35, and when the lever 41 is depressed, the shafts 39 and 40, together 90 with the brackets 35, are shifted transversely of the machine. On each end of the roller 28, is a ratchet wheel 45, having projecting outwardly from its outer surface two teeth 46. These teeth are designed to engage the bevel pinions 38, and when one of said ratchet wheels is in position in engagement with one of the bevel pinions 38, it will be rotated as the paper is advanced, and will turn the bevel pinion 38 two spaces during each 100 revolution of the ratchet wheel. This will be sufficient to advance the ribbon spools the desired amount, and when the lever 41 is operated in any direction to shift the ribbon device, the motion of the ribbon winding 105 spools will be reversed.

I have provided for advancing the paper roll 28 as follows: Fulcrumed to the machine frame at one side is a lever 47 having pivoted to its lower end a rod 48, provided with a 110 tooth 49. This tooth is normally in engagement with the ratchet wheel 45, and is so arranged that a movement of the lever 47 will turn the paper roll 28 the proper distance for spacing apart the lines in a column of 115 figures.

I have provided means for carrying totals from one type bearing segmental bar 13 to the others, and for visibly indicating to the operator at all times as follows: Mounted in 120 the machine frame 10 is a shaft 50 having a limited movement transversely of the machine and normally held to one limit of its movement, by means of a spring 51. Rotatably mounted upon this shaft 50 is a series of 125 type bearing wheels 52, one for each row of key bars. Each of these wheels 52 is provided with a row of type 53, consecutively arranged from 0 to 9, and between these type I have arranged a series of numerals 54, also 130

consecutively arranged from 0 to 9, so disposed with relation to the other numerals 53, that when the numeral 1 on one wheel is in printing position, that is adjacent to the hammer 32, the numeral 1 of the series 54 will stand directly beneath a small opening 55, formed in the top of the frame 10, where the operator may readily see it. Formed on one edge of each of the wheels 52, is a series 10 of ratchet teeth, 56. Rotatably mounted on the hub of each of the wheels 52, is a wheel 57, having cog teeth formed thereon, and ratchet teeth 59 formed thereon, adjacent to the teeth 58. Carried by each of the wheels 15 52 is a spring actuated pawl 60, designed to engage the adjacent set of ratchet teeth 59. Between each wheel 52 and the adjacent wheel 57, is a spacing washer 61, held against rotation on the shaft 50 by means of the arms 20 62 resting upon the support 63, as clearly shown in Fig. 7.

Formed within each of the wheels 52 is a circular recess 64, surrounding the shaft 50. In this recess is a lug 65, and fixed to the 25 shaft 50 is a pin 66. This pin 66 is normally in such position that the wheel 52 may freely rotate without having the pin 66 engage the lug 65. However, when the shaft 50 is moved longitudinally against the pressure of 30 the spring 51, the pin 66 will engage the lug 65, and thus cause the wheel 52 to rotate with the shaft 50. I have provided for manually moving the shaft 50, and for rotating it, as follows: Formed on the frame 10 is 35 a clutch member 67 surrounding the shaft 50. Fixed to the end of the shaft is a hand wheel 68, having a clutch member 69 formed thereon to coact with the clutch member 67. By means of this mechanism, if it is desired 40 to move all of the wheels 52 by hand, the operator grasps the hand wheel 68 and pulls it out of engagement with the clutch member 67, thus bringing all of the pins 66 into engagement with the lugs 65. He then 45 turns the hand wheel 68, and in this way moves all of the wheels 52. In this connection, it is to be understood that the lugs 65 are so arranged within the wheels 52, that when the shaft 50 has been turned a complete 50 revolution, with the clutch members 67 and 69 out of engagement, all of the wheels 52 will be moved to position with the numerals 0, all in printing position, and in position where they will be visible through the openings 55, so that in this way the machine may be cleared at any time.

I have provided means for carrying totals from one wheel to the next as follows: On the rear side of each of the wheels 52, is a 60 laterally projecting pin 70. Pivoted to the forward end of each of the arms 62, is a lever 71, having pivoted to its upper end an arm 72, formed with an inclined shoulder 73, and inclined shoulder 74. Pivotedly mounted on 65 top of the arm 72 is a spring actuated pawl

75, normally held by its spring in engagement with the ratchet teeth 56 of the adjacent wheel 52, to the left. Arranged below the arm 72 is a shaft 76, supported by the machine frame, and carrying a series of 70 pawls 77, each of which has two lateral projections 78 and 79 on one side, with a space between them. The operation of this carrying mechanism is as follows: When the first wheel to the right has been moved to position, with the numeral 9 thereon in its printing position and visible through the opening in the top of the frame, where the pin 70 is in position in engagement with the shoulder 74 of the pawl 72, as clearly shown in Fig. 2. Then when the wheel 52 is moved one type space further, the pin 70 will throw the arm 72 toward the front of the machine, and the pawl 75 connected to the arm 72 will cause the next wheel 52 to the left, to be moved 80 one type space. As soon as the arm 72 has been operated to move the adjacent wheel 52 one type space as above described, the inclined shoulder 73 of the arm 72, will strike upon the shaft 76, and thus elevate the arm 90 72 out of the path of the pin 70, as shown in Fig. 14, so that if the wheel 52 to the right should have been moved more than one type space, the wheel to the left will be moved 85 only one type space and no farther.

In clearing up the machine by turning the hand wheel 68 as before described, the pins 70 would be stopped in position in engagement with the shoulder 74 of the type wheels 52, and in order to start the machine in operation after it has been cleared, it is necessary that these pins 70 be in position past the shoulders 74 of the pawl 72. To provide for this actuated positioning of the wheels 52, I have placed on the shaft 76, a crank arm 80, designed to enter a notch 81 formed in a disk 81^a, fixed to the hub of the hand wheel 68, as clearly shown in Figs. 3 and 9. The arms 77, as before described, are fixed to this shaft 76, and they are so arranged that when the crank 100 arm 80 is resting in the notch 81, as shown in Fig. 3, the arms 77 will stand in the position shown in Fig. 14, and when they are in this position, the pins 70 may be passed through between the lugs 78 and 79 of the arms 77, 110 but when the hand wheel 68 is turned, then the rear end of the crank arm 80 will be elevated, thus bringing the arms 77 to the position shown in Fig. 15, where the pins 70 will strike against the lugs 79, and thus all of the 115 wheels 52 will be stopped in this position, which position is such that the pins 70 will be beyond the shoulders 74 of the arms 72, so that when starting to operate the machine after it has been cleared, the pins 70 will not 120 engage the shoulders 74 until after the wheels 52 have made a complete revolution, it being understood that as soon as the hand wheel 68 has completed its revolution, the arms 77 will again drop to the position shown 125 130

in Fig. 14, where the pins 70 will not interfere or engage with the arms 72, or the lugs thereon. In this connection, it is to be understood that when all of the wheels 52 have been turned to position, with the pins 70 thereon resting against the lugs 79 as shown in Fig. 15, all of the numerals 0 on the adding wheels will be in printing position, and be visible through the openings in the frame. The lugs 78 are for the purpose of engaging the lugs 73 on the arm 72, and holding the arm 72 in an elevated position, as shown in Fig. 15, so that the lugs 74 will not stand in the path of the pins 70.

From the foregoing description it will be understood that the printing of numerals in the first instance will be done from the type on the segmental bars 13. I have provided means for printing totals at any time direct from the wheels 52, as follows: I have described heretofore, the movable carriage on which the printing hammers 32 are mounted. These hammers normally stand in position to print from the type on the segmental bars 13, but they may be shifted as shown by dotted lines in Fig. 8, to position for printing from the type wheels 52. This mechanism comprises a key bar 82 in each column of key bars, normally held by a spring in the same way as the key bar 17, and each provided near their lower end with a lug 83. Mounted adjacent to the lug 83 is a shaft 84 having a forwardly projecting crank arm 85, to which a cross rod 86 is attached. This rod is in the path of the lugs 83 so that when the key 82 is depressed, the lug 83 will engage the rod 84 and push it downwardly. Fixed to the shaft 84 is a rod 87 connected to the crank arm 88 and a shaft 89, the lower end of which is provided with an arm 90 to enter a notch 91, formed in the sliding carriage 25, as shown in Fig. 18. In this way, the first effect of a downward movement of any of the key bars 82, will be to shift the carriage 25 to position with the hammers 32 opposite to the wheels 52. The next effect of a downwardly movement of any of these key bars 82, will be to have their lower ends strike upon the crank arms 23, and thus actuate the printing hammers. The said key bars are shown in this position in Fig. 11, by dotted lines. I have also provided means whereby the entire total may be printed by the depression of a single key, as follows: On each of the key bars 82 except the first one to the right, I have formed a lateral extension 92, to overlap a pin 93 formed on the adjacent key board to the right. By this means, and assuming that the total sum to be printed was in four figures, then the operator would depress the key bar 82 in the fourth row, and the extension 92 would engage the pins 93 and thus depress all four of the key bars to the right, as shown by dotted lines in Fig. 11.

In practical use, and assuming that the

machine is in its normal position, and assuming that the number 5555 is to be printed, then the operator depresses the key bearing the numeral 5, in the fourth column, then the key bearing the numeral 5 in the third column, then in the second, and then in the first. The printing will be done direct from the segmental bars 13, and the adding wheels 52 will have no part in the operation, except that they will each be moved by the pawls 60 so that the numerals thereon will stand in position with the numerals 5 on the first four wheels in printing position, and with the numerals 5 of the same wheels of the set shown in black in Fig. 8, appearing through the openings in the top of the frame. Then the operator depresses the lever 47, thus advancing the paper one line space, then the operator proceeds to print the next number in the same way. Assuming that the second number to be printed contains the last numeral of a value of five or more figures, then the printing is all done from the segmental bars in the same way as before described, but the carrying mechanism will cause the second adding wheel to the right to be moved one type space, thus carrying ten from the first wheel to the right, to the second wheel. The operator proceeds in this way until the column of figures to be added has been completed, then assuming that it is desired to print the total, and the total number comprises five figures, he then depresses the fifth one of the key bars 82, thus shifting the carriage to bring the printing hammers in operative position with relation to the adding wheels, and immediately thereafter operating the printing hammers jointly to print the total. Assuming that it is desired to return all of the adding wheels to normal position with the numerals 0 appearing in printing position through the openings in the frame, then the hand wheel 68 is grasped and moved to release the clutch members 67, and then rotated a complete revolution, this will have the effect of causing all of the pins 66 to engage the lugs 65, and thus move all of the adding wheels to the desired point, and at the same time it will operate the crank arm 80 in such manner as to bring the arms 77 into the path of the pins 70, thus positively stopping all of the adding wheels in the proper position, and at the same time allowing these pins 70 to pass the shoulders 74 of the arm 72 so that the machine will be in position for starting a new operation.

Having thus described my invention, what I claim and desire to secure by Letters Patent of the United States, therefor is—

1. In a machine of the class described, the combination of a lever, a series of key bars each capable of depressing the lever a different distance, a segmental bar fixed to said lever and having teeth on its concave side for operating an adding wheel of the machine,

- and printing type on its convex side, a printing hammer, and means for operating the printing hammer against said type, at the completion of the stroke of said lever.
5. 2. In a machine of the class described, the combination of a lever, a series of key bars, each capable of depressing the lever a different distance, a segmental type bearing bar fixed to the lever, a hammer to operate 70 against the type on the bar, and means for operating the hammer at completion of the movement of each key bar, said segmental type bearing bar formed with cog teeth on one side, an adding wheel and a pinion connected with the adding wheel, and in mesh with the said cog teeth, type on the adding wheel, and means for shifting the hammers to print from the type on the adding wheel. 75
3. In a device of the class described, the combination of a series of levers fulcrumed near their central portions, each having on one end a type bearing bar, a series of key bars for each lever, each capable of depressing the lever a different distance, a printing hammer for each key bar, means operated by any key bar for operating the hammer at the completion of the stroke of the key bar, a series of adding wheels having type thereon, a pinion operatively connected with each 80 adding wheel, said pinions being in mesh with the cog teeth on the type bearing bars, and means for shifting the hammers to print either from the type bearing bars, or from the adding wheels. 85
35. 4. In a device of the class described, the combination of a series of levers fulcrumed near their central portions, each having on one end a type bearing bar, a series of key bars for each lever, each capable of depressing the lever a different distance, a printing hammer for each key bar, means operated by any key bar for operating the hammer at the completion of the stroke of the key bar, a series of adding wheels having type thereon, a pinion operatively connected with each 90 adding wheel, said pinions being in mesh with the cog teeth on the type bearing bars, and means for carrying totals from one adding wheel to the next, and means for shifting the hammers to print from the type on the bars on the adding wheel. 95
40. 5. In a machine of the class described, the combination of a type bearing bar having teeth on one side, a series of key bars for operating the type bearing bars, an adding wheel at the side of the type bearing bar having type on its face and arranged for operation by said teeth, a hammer normally held in position for printing from the type on the type bearing bar, and means for shifting the hammer to position for printing from the type on the adding wheel. 100
45. 6. In a machine of the class described, the combination of a series of type bearing bars, each having teeth on one side, a key bar op- 105
- eratively connected with each type bearing bar, a series of adding wheels arranged to be operated by the teeth on the type bearing bars, means for carrying totals from one adding wheel to the other, each adding wheel having on its face a series of type, a series of hammers normally in position for printing from the type bars, and means for jointly shifting the hammers to position for printing from the adding wheels. 110
50. 7. In a machine of the class described, the combination of a series of type bearing bars, and the bars for operating each type bearing bar, a series of adding wheels having type thereon, means for operatively connecting the type bearing bars with the adding wheels, means for carrying totals from one adding wheel to the other, a movable carriage, paper holding and carrying mechanism thereon, a series of hammers on the movable carriage 115 normally in position for printing from the type bearing bars, and means for shifting the carriage to position with the hammers opposite to the type on the adding wheels. 120
55. 8. In a machine of the class described, the combination of a series of type bearing bars, a series of key bars for operating each type bearing bar, a series of adding wheels operatively connected with the type bearing bars, type on each adding wheel, means for carrying totals from one adding wheel to the other, a movable carriage paper supporting device thereon, a hammer on said carriage for each type bearing bar, means for shifting the carriage from position with the hammers 125 opposite to the type bearing bars, to position with the hammers opposite to the type on the adding wheels, and means operated by the key bars of each type bearing bar for operating the corresponding hammer at the completion of the stroke of any key bar, said means including the sliding connection with the hammer so that the operative connection between the hammers and said means is not effected by the shifting of the carriage. 130
60. 9. In a device of the class described, the combination of a series of type bearing bars, a series of key bars for operating each type bearing bar, a series of adding wheels operatively connected with the type bearing bars, and each containing type on its face, means for carrying totals from one adding wheel to the other, a movable carriage, a series of printing hammers mounted thereon and operatively connected with the key bars, and a 135 series of key bars, one for each of the type bearing bars, and means operated thereby for shifting the carriage from position with the hammers opposite to the key bars, to position with the hammers opposite to the type on the adding wheels. 140
65. 10. In a device of the class described, the combination of a series of type bearing bars, a series of key bars for operating each type bearing bar, a series of adding wheels opera- 145

- tively connected with the type bearing bars, and each containing type on its face, means for carrying totals from one adding wheel to the other, a movable carriage, a series of 5 printing hammers mounted thereon and operatively connected with the key bars, and a series of key bars, one for each of the type bearing bars, and means operated thereby for shifting the carriage from position with 10 the hammers opposite to the key bars, to position with the hammers opposite to the type on the adding wheels, an interlocking device on said latter set of key bars so arranged that a depression of any one of said series of 15 key bars will operate to depress all of the key bars to the right of the one depressed.
11. In a device of the class described, the combination of a series of type bearing bars, a series of key bars for operating each type 20 bearing bar, a series of adding wheels operatively connected with the type bearing bars, and each containing type on its face, means for carrying totals from one adding wheel to the other, a movable carriage, a series of 25 printing hammers mounted thereon and operatively connected with the key bars, and a series of key bars, one for each of the type bearing bars, and means operated thereby for shifting the carriage from position with 30 the hammers opposite to the key bars, to position with the hammers opposite to the type on the adding wheels, an interlocking device on said latter set of key bars, said interlocking device comprising a laterally projecting 35 lug on each key bar, and a pin on the adjacent key bar to the right, beneath the lug on the key bar to the left.
12. In a device of the class described, the combination of a shaft, a series of adding 40 wheels mounted on the shaft, and having ratchet faces on one side, means for operating the adding wheels, bars mounted on the shaft between the adding wheels, a jointed spring actuated arm extended upwardly 45 from each of said bars, and formed with a notch near one end, and an inclined shoulder near its central portion, a pawl carried by each of said spring actuated arms, to engage the ratchet faces of the adjoining adding
- wheels, a pin carried by each adding wheel 50 to engage the said shoulder of the spring actuated arm, and to move the arm, and with it the said pawl, a shaft in the path of said inclined shoulder to elevate the spring actuated arm out of contact with the pin, a series 55 of arms fixed to said latter shaft normally out of the path of said pins, and capable of being set to position in the path of the pins to stop all of the wheels in position with the pins of each in line. 60
13. In a device of the class described, the combination of a shaft, a series of adding wheels mounted on the shaft, and having ratchet faces on one side, means for operating the adding wheels, bars mounted on the shaft between the adding wheels, a jointed spring actuated arm extended upwardly 65 from each of said bars, and formed with a notch near one end, and an inclined shoulder near its central portion, a pawl carried by each of said spring actuated arms, to engage the ratchet faces of the adjoining adding wheels, a pin carried by each adding wheel to engage the said shoulder of the spring actuated arm, and to move the arm, and with 70 it the said pawl, a shaft in the path of said inclined shoulder to elevate the spring actuated arm out of contact with the pin, a series of arms fixed to said latter shaft normally 75 out of the path of said pins, and capable of being set to position in the path of the pins to stop all of the wheels in position with the pins of each in line, and means for rotating the shaft of the adding wheels, and at the same time moving said arms into the paths 80 of the said pins, said means comprising a notched disk fixed to the shaft of the adding wheels, and an arm fixed to the shaft of the arms that engage the pins, said arm normally resting in said notch, and moved to the 85 peripheries of the disk when the disk is turned.
